2,946,423

RIBBON SPOOL COVER ARRANGEMENT IN
TYPEWRITER

Henry B. Childs, Elmwood, Conn., assignor to Underwood Corporation, New York, N.Y., a corporation of Delaware

Filed Nov. 24, 1958, Ser. No. 775,902

5 Claims. (Cl. 197—186)

This invention relates to ribbon spool covers for typewriters in general, and, in a more specific sense, to ribbon spool covers for typewriters of the kind which embody an open-frame carriage reaching forwardly from the platen over the ribbon spool region for accommodation thereof of conveniently manipulative margin gaging devices.

It is old in typewriters of the stated kind to provide displaceable spool covers, but in all previously devised arrangements the spool covers in their uncovering positions stand in the path of movement of the carriage. Therefore if the carriage is inadvertently returned or otherwise moved before the restoration of the spool covers is effected, said covers will be scratched or bent, or the machine otherwise damaged. Most detrimentally also, prior covers in their uncovering positions infringe upon desirable free space for the efficient and convenient movement of the operator's hands in effecting placement and removal of the ribbon spools. Also, the spool cover structures used heretofore in machines of said stated kind are of inefficient structure and unsuitable for best enhancement of the aesthetic appeal of the machine.

It is therefore a main object of the invention to provide in connection with the kind of typewriter hereinabove referred to, ribbon spool covers advantageously correlated with other parts of the machine, and movably organized, to be in all respects fully satisfactory.

It is a further object of the invention to provide ribbon spool covers for a typewriter of the stated kind, which are efficiently movable to uncover the said spools in a manner so that no condition is ever created which gives cause to marring of such covers or other machine damage.

In connection with the stated kind of machine it is a further object of the invention to provide spool covers efficiently mounted and coordinated with other parts of the machine for movement to facilitate the loading or unloading of ribbon spools in a most convenient manner.

It is a more detailed object of the invention to provide in the stated kind of machine for the two ribbon spools, individual dust covers which are movable to uncovering positions generally parallel to the carriage, oppositely to facilitate the convenient installation or removal of ribbon spools, said covers being correlated with the frame and the carriage so as to facilitate always the free and unobstructed movement of the latter.

Other objects will become apparent as the description of a preferred embodiment of the invention proceeds.

In the drawings,

Figure 1 is a plan view of an Underwood standard typewriter embodying the spool covers of the invention, a right-hand spool cover being shown displaced laterally of the machine to facilitate spool access.

Figure 2 is a sectional side elevation of a right-hand upper portion of the typewriter seen in Figure 1, taken along a line 2—2 of Figure 1, and showing one of the ribbon spool covers of the invention, and finally,

Figure 3 is a front perspective view looking in a

2

rightward direction downwardly upon the right ribbon spool region and showing a cover moved rightwardly from over the ribbon spool.

Having now particular reference to Figure 1, a main frame 12 of the typewriter has a carriage 13 thereupon adapted to traverse it in a usual manner. Said carriage 13 comprises two spaced end pieces 14 upon which there is turnably supported a usual platen roll 15. The typewriter has a usual keyboard indicated at 16 and the main frame 12 includes opposite side walls 17.

Forwardly of the platen roll 15, between its spaced end pieces 14, the machine has two laterally spaced, substantially vertical spindles 18 upon each of which there is adapted to be placed a ribbon spool 20. In the 15 particular machine shown in the drawings, the spools are of the flanged kind, but, of course, unflanged spools may be used if the machine is designed to receive such spools. In a conventional manner typewriter ribbon 21 is adapted to be threaded through a usual ribbon vibrator 22 which 20 automatically lifts the ribbon incidental to each typing operation to present it at a usual printing point. Type bars 19 of a usual system arranged intermediate said spool spindles 18 strike at said printing point. The end pieces 14 of the carriage comprise arms 23 which reach 25 forwardly of the platen 15 over the general region occupied by the ribbon spools 20. Forwardly beyond said spools, a bar 24 of L-shaped cross section extends parallel to the platen and connects said arms 23. At the rear of the platen 15 the carriage end pieces 14 are rigidly 30 connected by a bar 25. The carriage end pieces 14, inclusive of the arms 23 and together with the bars 24 and 25 may be said to constitute an open carriage frame. The main frame 12 has upon the rear a carriage guiding rod 26 and furthermore has forwardly of the front bar 25 35 of the carriage, a track bar 27 having a channel insert 28 of U-shaped cross section.

Two spaced elements 30 on the rear bar 25 of the carriage have carriage guiding association with the rod 26. Rolls 31 on the front bar 24 of the carriage by 40 traveling in the channel insert 28 of the track bar 27 give supplemental carriage guidance. The front bar 24 of the carriage carries hidden thereby a rack bar 32 which supports adjustably thereon usual left and right 45 margin stops indicated at 33. Each such margin stop is releasable and adjustable along said rack bar 32 by a finger piece 34 which is situated directly behind the carriage bar 24. A frame supported counterstop indicated at 35 serves for margin gaging coaction with said margin stops 33.

50 The ribbon spool supporting spindles 18 turn each in vertically spaced bearings afforded by an upper platform 36 and a flange 37 thereunder, each related platform 36 and flange 37 being part of a bracket structure 39 which by screws 38 is attached to an internal rib 40 55 of the adjacent side wall 17. For simplicity of illustration, the ribbon spools 20 are shown to fit directly upon the top ends of the spindles 18. Furthermore, they rest each on a circular flange 41 of the spindle 18, each flange having an upwardly projecting spool driving 60 pin 42.

Individual dust covers 43 for said ribbon spools 20 underlie said carriage arms 23 for travel of the latter with clearance thereover. Each dust cover 43 overlies normally a general area between the platen 15 and the 65 front bar 24 of the carriage over one ribbon spool to the outer extremity of the machine side wall 17. A main portion of each cover 43 is generally horizontal and from such portion slopes a front portion 45 underneath the front bar 24 of the carriage in a generally contiguous 70 relationship thereto but clear thereof and the margin stop elements 33.

The ribbon spool covers 43 are each displaceable parallel to the platen 15 outwardly of the machine frame, that is parallel to the direction of movement of the carriage. This is to facilitate access to the ribbon spool locations for permitting the efficient loading or unloading of ribbon spools. Prior to effecting such operations the carriage 13 is approximately centered laterally upon the machine frame 17 as illustrated in Figure 1. Then by application of finger pressure against the inner extremities of the covers, said covers are pushed outwardly to extend to each side beyond the main frame. This renders the general ribbon spool area of the machine very open and free for ribbon spool handling, that is for ribbon spool removal or installation.

The structure for supporting said ribbon spool covers 43 for outward displacement is very simple and efficient. On each cover 43 there are channels 46 formed along their front and rear edges parallel to the carriage and facing generally toward each other. These channels fit oppositely guiding edges provided on opposite webs 47 of a trough-like member 50 which is preferably formed of springy material. Screws 51 secure said members 50 upon their related platforms 36. The said trough members 50 are made of flexing material, designed for their edges resiliently to press into the cover channels 46, whereby the covers are frictionally retained in whatever positions they may be moved to and will not rattle. At each side of the machine the side walls 17 reach upwardly into close relationship with the undersides of the covers 43, see particularly Figure 2, and thereby conceal each ribbon spool from the side. Installation of each cover 43 is effected by first hooking one of the cover channels 46 over the appropriate edge of the related member 50 and then pressing the cover in the direction of the other edge and downwardly. Each cover 43 has secured to its underside a motion limiting element 52. One end of such element 52 will limit outward motion of the cover by engagement with the inner side of the side wall 17 and the other end will limit inward motion by cooperation with a finger 53 which is upreaching from the platform 36. The stated finger 53 affords a usual ribbon guiding edge 54.

Having explained the nature and the objects of the invention, and having specifically described a machine embodying the invention in its preferred form, what is claimed is:

1. In a typewriter having a main frame, a platen roll and a system of front-strike type bars of which the individual bars are operable rearwardly against said platen roll; means on said frame forwardly of said platen roll, at each opposite side of said system of type bars and substantially within the lateral confines of said frame, to accommodate a spool of typewriter ribbon, a carriage on said main frame and supporting the said platen roll, means to guide said carriage on said main frame for travel parallel to the platen roll axis, said carriage having for substantially its full length, forwardly of said spool accommodating means, a bar extending parallel to the platen roll, margin stop means provided in association with said bar, a separate cover overlying normally each of said spool accommodating means and each cov-

ering thereat generally an area between the platen roll and said bar over a space which is required for the accommodation of a ribbon spool, said carriage having at each end of the platen a forwardly reaching arm supporting said bar and being formed to travel with clearance over said ribbon spool covers, and means to mount each of said covers for movement parallel of said platen roll from over the related spool accommodating means, outwardly of said main frame, thereby to facilitate the placement or removal of ribbon spools.

5 2. The invention set forth in claim 1, said cover mounting means comprising means oppositely on said main frame and said covers being cooperative to give said covers sliding support for outward movement.

3. The invention set forth in claim 1, said mounting means comprising cooperative means on said frame and said covers, along the front and rear edges of the latter, to lend sliding support to each cover for said outward movement.

15 4. The invention set forth in claim 1, each said mounting means comprising frame supported means affording a rear and a front guiding edge which face oppositely from each other and comprising further on said cover two channels facing toward each other and fitting oppositely said guiding edges to facilitate sliding movement of said covers outwardly of said main frame.

20 5. In a typewriter having a main frame, a platen roll and a system of front-strike type bars of which the individual bars are operable rearwardly against said platen roll; means on said frame forwardly of said platen roll, at each opposite side of said system of type bars and substantially within the lateral confines of said frame, to accommodate a spool of typewriter ribbon, a carriage on said main frame and supporting the said platen roll, means to guide said carriage on said main frame for travel parallel to the platen roll axis, said carriage having for substantially its full length, forwardly of said spool accommodating means, a bar extending parallel to the platen roll, margin stop means provided in association 25 with said bar, a separate cover overlying normally each of said spool accommodating means and each covering thereat generally an area between the platen roll and said bar over a space which is required for the accommodation of a ribbon spool, each of said covers having a generally planar main portion and having also a front portion which is downreaching from said main portion, said bar extending along the front of the downreaching portions of said covers, the said main frame having side walls which are upreaching to match closely the stated portion of said covers, said carriage having at each end of the platen a forwardly reaching arm supporting said bar and being formed to travel with clearance over said ribbon spool covers, and means to mount each of said covers for movement parallel of said platen roll from over the related spool accommodating means, outwardly of said main frame, thereby to facilitate the placement or removal of ribbon spools.
